UNITED STATES PATENT OFFICE.

JACQUES SILBERMANN, OF LEVALLOIS-PERRET, FRANCE.

DESIGN FOR A FIREPLACE.

40,318.

Specification for Design.

Patented Oct. 19, 1909.

Application filed September 23, 1908. Serial No. 454,474. Term of patent 7 years.

To all whom it may concern:

Be it known that I, JACQUES SILBERMANN, a citizen of the Republic of France, residing at Levallois-Perret, Department of the Seine, France, have invented a new, original, and ornamental Design for Fireplaces, of which the following is a specification, reference being had to the accompanying drawing, forming part thereof.

The figure is a front elevation of a fireplace showing my new design.

I claim:—

The ornamental design of a fireplace, as shown.

JACQUES SILBERMANN.
